UNITED STATES PATENT OFFICE.

BELLE ETTER CLEMENT, OF SEATTLE, WASHINGTON.

DESIGN FOR A SPANGLED TRIMMING.

49,051.

Specification for Design.

Patented May 16, 1916.

Application filed January 17, 1916. Serial No. 72,640. Term of patent 7 years.

To all whom it may concern:

Be it known that I, BELLE E. CLEMENT, a citizen of the United States, residing at Seattle, in the county of King and State of Washington, have invented a new, original, and ornamental Design for a Spangled Trimming, of which the following is a specification, reference being had to the accompanying drawing, forming part thereof.

The figure is a perspective view of an ornament, showing my new design.

I claim:

The ornamental design for a spangled trimming, as shown.

Miss BELLE ETTER CLEMENT.

Witnesses:

A. MILLIE REICH,

F. W. CRARY.
